REMOTE CONTROL UNIT FOR AN OUTBOARD MOTOR OR THE LIKE

Carl Knuth, Fond du Lac, Wis.

Application February 28, 1955, Serial No. 34,785

Term of patent 14 years

(Cl. D71—1)

FIG. 2.

FIG. 1.

FIG. 3.

Fig. 1 is a front elevation view of a remote control unit for an outboard motor or the like, showing my new design;

Fig. 2 is a side elevation view of the design shown in Fig. 1; and

Fig. 3 is a top plan view of the unit shown in Fig. 1 with the hand levers omitted for convenience of illustration. The rear elevation view of the unit is substantially the same as the front elevation view. The essential features of the design reside in the portions shown in full lines.

I claim:

The ornamental design for a remote control unit for an outboard motor or the like, as shown and described.
